Primary Examiner — Mary Ann Calabrese(74) *Attorney, Agent, or Firm* — Dennis D. Brown; Brown Patent Law, PLLC(57) **CLAIM**

The ornamental design of the advertising billboard, as shown and described.

DESCRIPTION

FIG. 1 is a perspective view of the advertising billboard illustrating my new design.

FIG. 2 is a front elevational view thereof.

FIG. 3 is a rear elevational view thereof.

FIG. 4 is a left side elevational view thereof.

FIG. 5 is a right side elevational view thereof.

FIG. 6 is a top view thereof; and,

FIG. 7 is a bottom view thereof.

The broken lines shown in the drawings represent unclaimed portions of the design and form no part thereof.
